UNITED STATES PATENT OFFICE

HERBERT W. CHENEY, OF MILWAUKEE, WISCONSIN, ASSIGNOR TO ALLIS-CHALMERS MANUFACTURING COMPANY, OF MILWAUKEE, WISCONSIN, A CORPORATION OF DELAWARE

AUTOMATIC MOTOR STARTER

Application filed June 7, 1920, Serial No. 337,237. Renewed July 6, 1925.

This invention relates to motor starters and particularly to that type which is automatic in operation. One of the objects of the invention is the provision of a motor starter 5 of simple and efficient construction and operation. Another object is the mutual simplification of the contact mechanism and the operating mechanism therefor. Another object is the provision of a motor starter which 10 will open when no voltage or low voltage obtains on the line but in which the usual additional no voltage magnet has been eliminated. Another object is the provision of a construction in which comparatively small control 15 magnets are permissible. Another object is the provision of a mechanism in which the operation of the running control magnet is made dependent upon the armature of the starting control magnet remaining in the 20 same position. In connection with this object it is a further object that the construction be such that the starter will return to off or circuit opening position from either its starting or running position upon the occurrence of low voltage on the line. Other 25 objects will appear hereinafter as the description of the invention proceeds.

The novel features of the invention will appear from this specification and the accompanying drawing forming a part thereof and disclosing one embodiment of the invention and all these novel features are intended to be pointed out in the claims.

The single figure of the drawing is a dia- 35 grammatic showing of an automatic starter embodying the features of the invention.

In the drawing, the starter has been shown as applied to a three-phase motor 1, it being understood, however, that the starter 40 may be readily applied to motors of other types. The starter provides, in general, for a connection of the leads 2, 3, 4 of the motor 1 to the line conductors 5, 6, 7, first through a transformer for starting purposes and then 45 directly to the line conductors for running. The main contacts of the starter include starting, running and movable co-operating contacts. Contacts, 8, 9 of the starting contacts are connected to auto transformer 10 50 and the contacts 11, 12 connected to the auto

transformer 13. Of the stationary running contacts, contact 14 is connected to starting contact 15 and these contacts are together connected to lead 2 of the motor. Contacts 16 and 17 are connected to the motor leads 55 3, 4 respectively through overload coils 19, 18 respectively. Of the movable contacts, all of which are carried by a single switch member, to be hereinafter more fully described, contacts 20, 21, 22 are connected together and 60 through a flexible lead 23, in any suitable manner to the line conductor 5. Contacts 24 and 26 are connected to line conductors 7, 6 respectively by means of flexible leads 25, 27 respectively, in like manner. For the 65 sake of clearness the switch member 28 for the movable contacts has been shown in side elevation as have also the starting and running contacts, the movable contacts *m* being co-operable with starting contacts *s* and running contacts *r*. The operating mechanism of the movable switch member 28 is so 70 designed that contact may be made between the movable contacts and either the starting or running contacts. The movable switch member 28 is pivoted in any suitable manner as 75 on the pin 30 carried by the actuating lever 29. The lever 29 is here shown as rigidly associated with the shaft 35, it being, however, understood that any other suitable 80 means may be utilized for transmitting motion to the lever 29. The movable switch member 28 is provided with an extension 31, which has pivoted thereto at 32 a lever 33 85 rotatable about the stationary pivot 34. It will be clear that if the lever 29 is swung in a clockwise direction the movable contact *m* will be shifted to the left and by reason 90 of the action of the lever 33, also in an upward direction, so that at the end of the motion, butt contact, with a slight final sliding motion will be made with starting contacts *s*. If the lever 29 is swung in a counter-clockwise direction from the position shown 95 in the figure, the movable contacts will in a similar manner be moved into contact with the running contacts *r*. The operating mechanism heretofore explained in its broad aspects is fully set forth in applicant's copending application S. N. 334,887 filed Oct. 29, 100

1919, now Patent No. 1,574,417, issued February 23, 1926, and reference may be had to that patent for a fuller description of one of the forms which it may take.

5 The starter is provided with a starting control coil 36 and a running control coil 37 which coils are here shown as mounted on the outer legs of an M-shaped core 41. The coils 36, 37 may act on an armature having legs 38, 39 mounted for pivotal movement on the central leg 40 of the core. The armature 38, 39 is operatively connected to the shaft 35.

10 For setting the starter into operation a control switch 42, which may be actuated in any desired manner but here shown as of the manual type, is provided. One contact of this switch is connected by means of conductor 43 to the line conductor 5, and the other contact is connected to the conductor 56 and one 15 of the contacts of a control switch 44, the purpose of which latter in this instance, as will be more fully set forth, is to cause such operation of the starter as will open the circuit of the controlled motor. The other contact of the switch 44 is connected to conductor 20 45 which is in turn connected to one terminal of the coil 36, and also to one terminal of the coil 37. The other terminal of coil 36 is connected to conductor 46 which is in turn 25 connected to one of the lower contacts 47 of what may be termed a transfer switch 48. The other lower contact 49 of the transfer switch is connected through conductor 50 to line conductor 6. A shunt circuit is provided 30 for the switch 42 comprising conductor 51, shunt switch 52 (which has stationary contacts 53, 54) holding coil 55 and conductor 56.

35 The shunt switch 52 is associated with a bell crank 57 which is swingable by means of 40 the rod 58 which has a lost motion connection 59 with a projection or pin movable in unison with the armature 38, 39. The shunt switch 52 is also operable by means of a core 61 associated with holding coil 55.

45 The transfer switch 48 is operable by means of a core 62 associated with the holding coil 55 by means of a lever 63 acting upon the rod 64 which carries the transfer switch member. The transfer switch is biased, by a spring 65, 50 to a position where the contacts 47, 49 are bridged and is held in its biased position, when the starter is in open circuit position, by means of a latch 66 which is engageable with the projection 67 on the rod 64. The 55 latch 66 may be pivoted at 68 so as to provide for a free passage of the projection 67 in a downward direction, any suitable means being provided for holding the latch in the position shown on the drawing. The upper 60 contacts 70, 69 of the transfer switch are connected to conductors 50 and 71 respectively. Conductor 71 is connected to one terminal of the coil 37, the other terminal of which is connected by conductor 72 to conductor 45.

65 A rod 73 having an abutment 74 at one end

thereof is here shown pivotally associated with the leg 38 of the armature. Surrounding this rod is a member 75 here indicated as of tubular form having an opening 76 through which the rod 73 passes. A spring 77 is disposed between the abutment 74 and the upper end of the tube 75. A rod 78 is associated with the tube 75 and forms at its lower end a piston rod 79 for the stationary dash pot 80. The rod 78 is also provided with a lug or projection 81 which is coactable with one arm of a bell crank lever 82. The other arm of this bell crank lever has pivotally connected thereto a rod 83 associated with the latch 66.

75 The armature 38, 39 is provided with a centering spring 84 attached thereto in such manner that when the coils 36, 37 are de-energized the armature will assume its mid-position and cause the movement of the movable switch member to off position.

80 An impedance coil 86, the purpose of which will be hereinafter set forth, is provided in the circuit including the conductor 88 in which are also included relay contacts 89, 90. The other terminal of the impedance 86 is connected to the conductor 87 which is in turn connected to the conductor 56. The conductor 88 is connected to the stationary running contacts 16. The relay contacts 89, 90 are bridgeable by relay switches 93, 94 respectively which are operable by the cores 91, 92 associated with coils 18, 19 respectively.

85 The operation is as follows:

90 When the parts are in the open circuit position as shown in the drawing and it is desired to start the motor, the control switch 42 is operated to its closed position, the starting control coil 36 being then energized by reason of the completion of the following circuit; from line conductor 5, conductor 43, switch 42, switch 44, conductor 45, coil 36, conductor 46, transfer switch 48 through contacts 47, 49, conductor 50 to line conductor 6. Energization of the coil 36 will cause the leg 95 38 of the armature to swing in a clockwise direction thereby swinging the movable contacts 20, 21, 22, 24, 26 into engagement with the stationary starting contacts 12, 9, 15, 11, 8 respectively, in the manner already hereinbefore noted, thus connecting the motor 1 to the line through the auto-transformers 10, 13 for starting purposes, as will be clear to those skilled in the art. The movement of the leg 38 of the armature causes the spring 77 to 110 be put under compression thus storing energy therein. If the leg 38 remains in its attracted position, the spring 77 will commence to expand, giving up its stored energy, and thereby lifting the tube 75. Inasmuch as the movement of the tube 75 is retarded in the upward direction by the dashpot 80, this movement will take place slowly. In its clockwise movement the leg 38 of the armature, by reason of the connection between it and the rod 115 120 125 130

58, will cause the closure of shunt switch 52. A by-pass or shunt is thereby established around the control switch 42 by conductor 51, shunt switch 52, coil 55 and conductor 56. It is therefore immaterial whether the operator ⁵ now releases the control switch 42 or not, the starting operation will nevertheless automatically continue. A new circuit is now established through the starting control coil 36 and the holding coil 55, as follows: conductor 43, conductor 51, shunt switch 52, holding coil 55, conductor 56, switch 44, conductor 45, coil 36, conductor 46, transfer switch 48 through contacts 47, 49 to conductor 50. The starting control coil therefore remains energized. Energization of the holding coil 55 also exerts a pull on the core 62 and therefore tends to move the transfer switch 48 in an upward direction, this movement, however, being prevented by means of the latch 66. Meanwhile, the upward motion of the tube 75 has continued and when the projection 81, operatively associated therewith, reaches the bell crank lever 82, the latch 66 will be withdrawn to the left thereby releasing the transfer switch which is pulled upwardly by the core 62. The transfer switch 48 is thereby moved into contact with the upper contacts 69 and 70 ²⁰ hereof, thereby energizing the running control coil 37 through the following circuit: conductor 43, conductor 51, shunt switch 52, holding coil 55, conductor 56, switch 44, conductor 45, conductor 72, running control coil 37, conductor 71, transfer switch 48 through contacts 69 and 70 to conductor 50. This circuit, it will be noted, is fed from line conductors 5, 6. The circuit of the starting control coil 36 is, of course, by the same movement, broken by the transfer switch leaving the contacts 47, 49. The coil 37 now acts upon the leg 39 of the armature to cause the same to swing in a counter-clockwise direction and when it has moved a sufficient distance, the shunt switch 52, opens by reason of the movement of the rod 58 to the right caused by the operative connection between said rod and the armature. The opening of the shunt switch 52 causes de-energization of the holding coil 55 and the transfer switch 48 would again drop but for the fact that the projection 85 on the leg 39 of the armature now engages the left hand end of the lever 63, thereby holding the transfer switch in engagement with its contacts 69 and 70. At the same time, a new circuit, which may be termed a "running" circuit, is established through the running control coil 37 by reason of the engagement of movable contact 24 with stationary running contact 16 as follows: relay contacts 94, 93, conductor 88, impedance coil 86, conductor 87, conductor 56, switch 44, conductor 45, conductor 72, coil 37, conductor 71, transfer switch 48 through contacts 69, 70, to conductor 50. This circuit, it will be noted, is

fed from line conductors 6, 7. It will be observed that the impedance coil 86 is now connected in series with the running control coil 37 and this connection occurs when the movable contacts 22, 24, 26 of the controller have been moved into engagement with the stationary running contacts 14, 16 and 17 respectively, thus connecting the motor directly to the line. In other words, when the leg 39 of the armature is in the position shown in the drawing the full power of the coil 37 is utilized to bring it to fully attracted position and when that position has been reached the current therethrough is cut down by the impedance coil for purposes of economy of current. The coil 86 may also be wound on the same core as the coil 37 so that the current flowing therethrough will also provide an additional magnetic effect to assist the coil 37 in holding the armature in its attracted position. ⁷⁰ ⁷⁵ ⁸⁰ ⁸⁵

If it is desired to prolong the starting period, all that is necessary is to keep the control switch 42 closed, thereby shunting holding coil 55 and preventing energization thereof. The starting control coil will thus be maintained energized through switch 42 and even after latch 66 releases the transfer switch the latter will not move inasmuch as coil 55 is not energized. As soon as switch 42 is released or opened, coil 55 will no longer be shunted and will actuate transfer switch 48, and the running connection will be made as already set forth hereinbefore. ⁹⁰ ⁹⁵

If it is desired to stop the motor, the switch 44 is operated to its open position and, as may be seen from the circuit hereinbefore traced through the coil 37, the latter will be thereby de-energized and all of the parts will return to the position shown in the drawing. In view of the fact that the relays 93, 94 are also included in the "running" circuit of the coil 37, the latter will also be de-energized when either of these relays is operated to open position by an overload on the motor causing effective energization of the coils 18, 19. It is moreover pointed out that inasmuch as the running control coil 37 is at first fed from line conductors 5, 6 through a circuit which does not include the abnormal-condition relay contacts and then from lines 6, 7 through a circuit which does include these contacts, there will be no possibility of the coil 37 being de-energized by reason of a momentary overload until the motor is directly connected to the line. ¹⁰⁰ ¹⁰⁵ ¹¹⁰ ¹¹⁵ ¹²⁰

By reason of the fact that the running control coil 37 is at all times during the operation of the motor connected to the line, it will be de-energized by a predetermined low voltage on the line and the parts will therefore also assume the open circuit or off position under these conditions. It will moreover be observed that if low voltage obtains on the line during the starting operation, that is, ¹²⁵ ¹³⁰

5 during the time that the leg 38 of the armature remains in attracted position with respect to the coil 36, the parts will also assume the open circuit position, thereby cutting out the motor, by reason of the resultant de-energization or effective weakening of the coil 36. The same result may be secured by actuation of the switch 44 to its open circuit position for, as may be seen by referring to the 10 circuit, previously traced, through coil 36 during the starting operation, the switch 44 is included in that circuit.

15 It will be noted that the closing of an energizing circuit through the running control coil 37 by the transfer switch 48 depends upon the continued energization of the starting control coil 36 for a predetermined time, that is, the armature 38 must remain in its attracted position with respect to coil 36 a time determined by the time element of the dashpot 20 80. If low voltage should obtain on the line thus weakening or de-energizing coil 36 the armature 38 will rotate in a counter-clockwise direction and the tube 75 will drop back. The 25 projection 81 will therefore not have reached the bell crank 82 to withdraw the latch 66 to thereby release transfer switch 48. If full line voltage should now again appear there is no possibility that, merely by reason of 30 this fact, the controller will be operated to its running position, as may occur in certain instances of the prior art. It would be necessary to again close switch 42, thus moving the controller to starting position.

35 It will be noted that by reason of the fact that the single set of movable contacts make butt contact with both starting and running stationary contacts, it has been possible to simplify the automatic operating mechanism of the controller, and much smaller operating coils are necessary.

40 It should be understood that it is not desired that the invention claimed be limited to the exact details of construction shown and described, for obvious modifications may occur to a person skilled in the art.

45 It is claimed and desired to secure by Letters Patent:

50 1. In a device adapted to control the starting of a motor, comprising a voltage reducing means, a switch movable in one direction for connecting said motor to said voltage reducing means to start the same and in a reverse direction for connecting said motor directly to its source of supply, electromagnetic 55 actuating means for said switch, means for initiating movement of said actuating means to starting position, means for maintaining said actuating means in starting position a predetermined time independently of said initiating means, and means responsive to the movement of said actuating means for reversing the direction of said movement.

60 2. In an automatic motor starter of the type for connecting a motor first through a

transformer to the line and then directly to the line, starting and running coils, a unitary armature therefor, means for closing the circuit of said running coil, and means associated with said armature for causing operation of said circuit closing means a predetermined time after said armature has moved to starting position while said armature remains in the same position.

65 3. In an automatic motor starter of the type for connecting a motor first through a transformer to the line and then directly to the line, starting and running coils, a unitary armature therefor, means for closing the circuit of said running coil, and energy-storing 70 means associated with said armature for causing operation of said circuit closing means a predetermined time after said armature has moved to starting position while said armature remains in the same position.

75 4. In an automatic motor starter of the type for connecting a motor first through a transformer to the line and then directly to the line, starting and running coils, a unitary armature therefor, means for closing the circuit of said running coil, and a spring associated with said armature put in energy-stored condition by movement of said armature to starting position, retarding means 80 connected to said spring, and means associated with said retarding means for causing actuation of said circuit closing means whereby said circuit closing means is actuated a predetermined time after said armature has reached starting position while said armature 85 remains in the same position.

90 5. In an automatic motor starter of the type for connecting a motor first through a transformer to the line and then directly to the line, a starting coil, an armature therefor, means for closing the circuit of said coil, means associated with said armature for shunting said circuit closing means, and means other than said armature for holding 95 said shunting means closed.

100 6. In an automatic motor starter of the type for connecting a motor first through a transformer to the line and then directly to the line, a starting coil, a running coil, an armature for said coils, means for closing the 105 circuit of said starting coil, and means associated with said armature for shunting said circuit closing means, and means for establishing a circuit for said running coil through said shunting means.

110 7. In a motor controller of the type controlled by an abnormal-condition relay having contacts, said contacts connectible to a supply line, a running control coil, means for connecting said running coil directly to the line and then for normal running condition connecting it to the line through said abnormal-condition relay contacts.

120 8. In a motor controller having running contacts electrically connectible to a supply 130

line, a running control coil, means for connecting one terminal of said coil to said line and for then connecting said terminal to one of said running contacts.

5 9. In a motor controller having starting and running contacts electrically connectible to a supply line having a plurality of conductors, a running control coil, means for changing the connection of said coil to the line from one conductor to another when the controller changes position from starting to running whereby the nature of control of said coil is changed.

10 10. In a motor controller having starting and running contacts electrically connectible to a supply line, a running control coil having two possible circuit connections to the line, a switch common to said connections for closing the circuit of said running coil, and means for maintaining said switch closed and one of said connections complete while the controller moves from starting to running position.

15 11. In a motor controller having starting and running contacts electrically connectible to a supply line, a running control coil having two possible circuit connections to the line, a switch common to said connections for closing the circuit of said running coil, means for maintaining said switch closed and one of said connections complete while the controller moves from starting to running position, and means controlled by said controller for opening said connection and establishing the other connection when said controller reaches running position.

20 12. In a motor controller having starting and running contacts electrically connectible to a supply line, a running control coil having two possible circuit connections to the line, means for maintaining one of said connections while the controller moves from starting to running position, means controlled by said controller for opening said connection and establishing the other connection when said controller reaches running position, and abnormal-condition relay contacts in said other connection.

25 13. In a motor controller having starting and running contacts electrically connectible to a supply line, a running control coil having two possible circuit connections to the line, means for maintaining one of said connections while the controller moves from starting to running position, means controlled by said controller for opening said connection and establishing the other connection when said controller reaches running position, and a resistance in said other connection.

30 14. In a motor controller having a starting and a running coil and energizing connections therefor, starting and running contacts, a single movable switch member adapted to make butt contact with either the start-

ing or running contacts, means for transferring energizing connection from said starting coil to said running coil, and means associated with and dependent upon energization of said running coil for maintaining the connection through said coil.

35 15. In an automatic starter adapted to control an asynchronous motor, comprising a single movable switch having a single set of contacts adapted to connect the motor to either a voltage-reducing device for starting or directly to the line for running, a starting coil, a running coil, an armature associated with said coils, means for operatively connecting said armature and said switch, connections between said coils and the line, a normally closed switch for controlling the circuits of both of said coils, a normally open switch for controlling the circuit of said starting coil, a switch for transferring the line connection from said starting coil to said running coil, said switch being biased to connect the starting coil to the line, means for holding said transfer switch in its biased position, energy-storing means associated with said armature and put in energy-stored condition by movement of said armature to starting position, retarded means operated by the stored energy of said energy-storing means for releasing said holding means after a predetermined time, a switch for shunting said normally open switch, a coil in said shunt circuit, means operated by said coil for operating said transfer switch against its bias, and means operatively associated with said armature for closing said shunt switch when said armature is operated to starting position.

40 16. In an automatic motor starter having starting and running positions, starting and running coils, starting and running contacts, unitary movable contact means, operatively associated with said coils, for making butt contact with either said starting or running contacts, means for closing the circuit of said starting coil and means responsive to the movement of said contact means for closing the circuit of said running coil a predetermined time after the closure of the starting coil circuit.

45 17. In an automatic motor starter having off, starting and running positions, starting and running coils, starting and running contacts, unitary movable contact means, operatively associated with said coils, for making butt contact with either said starting or running contacts, means for closing the circuit of said starting coil, means for closing the circuit of said running coil a predetermined time after the closure of said starting coil circuit, and means for biasing said movable contact means to off position whereby when said running coil is deenergized, said movable contact means will return to off position.

18. In an automatic motor starter having starting and running positions, starting and running coils, means for closing the circuit of said starting coil, means for shunting said circuit closing means, and a switch for opening the circuit of said starting coil and closing the circuit of said running coil through said shunting means. 5 70
19. In an automatic motor starter having starting and running positions, starting and running coils, means for closing the circuit of said starting coil, means for shunting said circuit closing means, a switch for opening the circuit of said starting coil and closing the circuit of said running coil through said shunting means, and means for opening the circuit of said shunting means upon energization of said running coil. 10 75
20. In an automatic motor starter having starting and running positions, starting and running coils, means for closing the circuit of said starting coil, means for shunting said circuit closing means, a switch for opening the circuit of said starting coil and closing the circuit of said running coil through said shunting means, and means for holding said switch in its last named position and for opening the circuit of said shunting means upon energization of said running coil. 15 80
21. In an automatic motor starter having starting and running positions, starting and running coils, means for closing the circuit of said starting coil, means for shunting said circuit closing means, means for transferring energization from said starting to said running coil through said shunting means, means for opening the circuit of said shunting means upon energization of said running coil, and means, upon the opening of said 20 85
- 40 shunt circuit, for introducing an impedance into the circuit of said running coil. 35 90
22. In an automatic motor starter having starting and running positions, starting and running coils, means for closing the circuit of said starting coil, a switch for opening the circuit of said starting coil and closing the circuit of said running coil, means for shunting said circuit closing means upon energization of said starting coil, means for 45 95
- 50 operating said transfer switch a predetermined time after said energization, means whereby upon initial operation of said switch said running coil is energized through said shunting means, and means responsive to the 55 energization of said running coil for opening the circuit of said shunting means and establishing another circuit for said running coil. 60 100
23. In an automatic motor starter having starting and running positions, starting and running coils, means for closing the circuit of said starting coil, a switch for transferring energization from said starting to said running coil, means for shunting said circuit closing means upon energization of said starting coil, means for operating said transfer 65 105
- switch a predetermined time after said energization, means whereby upon the operation of said transfer switch said running coil is energized through said shunting means, and means responsive to the energization of said running coil for opening the circuit of said shunting means and establishing a circuit through an impedance for said running coil. 70 110
24. In an automatic motor starter having starting and running positions, starting and running coils, means for closing the circuit of said starting coil, a switch for transferring energization from said starting to said running coil, means for forming a shunt circuit around said circuit closing means upon energization of said starting coil, said shunt circuit including a magnet and means whereby a predetermined time after energization of said starting coil said magnet operates said transfer switch. 75 115
25. In an automatic motor starter having starting and running positions, starting and running coils, means for closing the circuit of said starting coil, a switch for transferring energization from said starting to said running coil, said transfer switch being biased to a position where it closes the circuit of said starting coil, means energized in response to the energization of said starting coil tending to move said transfer switch against said bias, and means operative a predetermined time after energization of said starting coil for permitting effective action of the means tending to move said transfer switch. 80 120
26. In an automatic motor starter having starting and running positions, starting and running coils, means for closing the circuit of said starting coil, means including electro-responsive means for shunting said circuit closing means, a switch for transferring energization from said starting coil to said running coil, means for releasably holding said transfer switch in starting position, and means operative a predetermined time after energization of said starting coil for releasing said holding means whereby said electro-responsive means operates said transfer switch. 85 125
27. In an automatic motor starter having starting and running positions, starting and running coils, means for closing the circuit of said starting coil, a switch for transferring energization from said starting to said running coil, said transfer switch being normally biased to starting position, means for operating said transfer switch a predetermined time after energization of said starting coil, and means responsive to movement of said controller to running position for holding said transfer switch in running position. 90 130
28. In an automatic motor starter having starting and running positions, a starting coil, a running coil, an armature for said 95 135

5 coils movable in one direction to cause the starting connections to be made and in another direction to cause the running connections to be made, means for closing the circuit of said starting coil, means associated with said armature for shunting said circuit closing means, and means in circuit with said shunting means for holding the latter closed.

10 29. In an automatic motor starter of the type for connecting a motor first through a transformer to the line and then directly to the line, a starting coil, a running coil, an armature for said coils, means for closing the circuit of said starting coil, means associated with said armature for shunting said circuit closing means, means for establishing a circuit for said running coil through said shunting means, and means in circuit with said shunting means for holding the latter closed.

15 30. In an automatic motor starter having starting and running positions, a starting coil, a running coil, an armature for said coils movable in one direction to cause the starting connections to be made and in another direction to cause the running connections to be made, means for closing the circuit of said starting coil, means associated with said armature for shunting said circuit closing means, means for establishing a circuit for said running coil through said shunting means, and means in circuit with said shunting means for holding the latter closed.

20 31. In an automatic motor controller having two operative positions, a control coil for each of said positions, a control switch for one of said coils, an armature for said last named coil, means associated with said armature for shunting said control switch, and means for interrupting the circuit through said coil and establishing a circuit for the other coil through said shunting means.

25 32. In an automatic motor starter having starting and running positions, starting and running coils, a control switch for closing the circuit of said starting coil, a switch for transferring energization from said starting to said running coil, means for shunting said control switch including an electromagnet and a core therefor and a second core for said electromagnet operatively associated with said transfer switch.

30 33. In an automatic motor starter of the type for connecting a motor first through a voltage reducing device to the line and then directly to the line, electromagnetically operated actuating means therefor including an operating coil for causing the starter to make the starting connections, a control switch for closing the circuit of said operating coil, a relay contact in the circuit of said operating coil, a shunt coil operatively related to said relay contact for actuating said contact to thereby deenergize said operating coil, means

whereby the movement of said starter to starting position causes energization of said relay coil, and means for delaying said actuation of said relay contact by said relay coil after said coil has been energized.

34. In an automatic motor starter of the type for connecting a motor first through a voltage reducing device to the line and then directly to the line, electromagnetically operated actuating means therefor including an operating coil for causing the starter to make the starting connections, a control switch for closing the circuit of said operating coil, a relay contact in the circuit of said operating coil, a shunt coil operatively related to said relay contact for actuating said contact to thereby deenergize said operating coil, means whereby the movement of said starter to starting position causes energization of said relay coil, and means for preventing said actuation of said relay contact by said relay coil after said relay coil has been energized, until the occurrence of predetermined conditions.

35 35. In an automatic motor starter of the type for connecting a motor first through a voltage reducing device to the line and then directly to the line, electromagnetically operated actuating means therefor including an operating coil for causing the starter to make the starting connections, a control switch for closing the circuit of said operating coil, a relay contact in the circuit of said operating coil, a coil operatively related to said relay contact for actuating said contact to thereby deenergize said operating coil, means whereby the movement of said starter to starting position causes energization of said relay coil, and means for delaying for a predetermined time said actuation of said relay contact by said relay coil after said coil has been energized.

40 36. In an automatic motor starter having a single movable switch member for connecting a motor first through a voltage reducing device to the line and then directly to the line, electromagnetically operated actuating means therefor including a starting coil for causing the starter to make the starting connections and a running coil for holding the starter in the running position, a control switch for closing the circuit of said starting coil, a relay contact in the circuit of said starting coil, a coil operatively related to said relay contact for actuating said contact to thereby deenergize said starting coil, means whereby the movement of said starter to a starting position causes energization of said relay coil, means for delaying said actuation of said relay contact by said relay coil after said coil has been energized, a contact in the circuit of said running coil, a spring for biasing said starter away from the starting position, and means operatively associated

with said starter and said contact in the circuit of said running coil.

37. In an automatic motor starter of the type for connecting a motor first through a voltage reducing device to the line and then directly to the line, electromagnetically operated actuating means therefor including an operating coil for causing the starter to make the starting connections, a control switch for closing the circuit of said operating coil, a relay contact in the circuit of said operating coil, a coil operatively related to said relay contact for actuating said contact to thereby deenergize said operating coil, means whereby the movement of said starter to starting position causes energization of said relay coil, a latch for releasably holding said relay contact in the closed position, and means responsive to the movement of said starter, for releasing said latch to thereby permit said relay coil to open said relay contact, after said relay coil has been energized.

38. In an automatic motor starter of the type for connecting a motor first through a voltage reducing device to the line and then directly to the line, electromagnetically operated actuating means therefor including an operating coil for causing the starter to make the starting connections, a control switch for closing the circuit of said operating coil, a relay contact in the circuit of said operating coil, a coil operatively related to said relay contact for actuating said contact to thereby deenergize said operating coil, means whereby the movement of said starter to starting position causes energization of said relay coil, a latch for releasably holding said relay contact in the closed position, and means for releasing said latch to thereby permit said relay coil to open said relay contact a predetermined time after said relay coil has been energized.

39. In an automatic motor starter of the type provided with a voltage reducing device, switch contacts mechanically connected together for connecting a motor through said voltage reducing device to a line and means including other contacts for connecting said motor directly to the line, electromagnetically operated actuating means for said starter including two operating coils for causing the starter to make the starting and running connections respectively, a control switch for closing the circuit of said starting operating coil, a relay contact initially in the circuit of said starting operating coil and movable into the circuit of said running operating coil, a shunt coil operatively related to said relay contact for actuating said contact to thereby deenergize said starting operating coil and energize said running operating coil, means whereby movement of said starter to starting position causes energization of said relay coil, means for delaying said actuation of said relay contact by said relay coil after

said coil has been energized, and means including said relay contact for maintaining said relay contact in said actuated position after actuation thereof.

40. In an automatic motor starter of the type provided with a voltage reducing device, switch contacts mechanically connected together for connecting a motor through said voltage reducing device to a line and means including other contacts for connecting said motor directly to the line, electromagnetically operated actuating means for said starter including two operating coils for causing the starter to make the starting and running connections respectively, a control switch for closing the circuit of said starting operating coil, a relay contact initially in the circuit of said starting operating coil and movable into the circuit of said running operating coil, a shunt coil operatively related to said relay contact for actuating said contact to thereby deenergize said starting operating coil and energize said running operating coil, means whereby movement of said starter to starting position causes energization of said relay coil, means for delaying said actuation of said relay contact by said relay coil after said coil has been energized, and means for maintaining said relay coil energized after actuation of said relay contact including a circuit through said relay contact in its running position.

In testimony whereof, the signature of the inventor is affixed hereto.

HERBERT W. CHENEY.
